UNITED STATES PATENT OFFICE

2,546,761

RADIUM NASOPHARYNGEAL APPLICATOR

George H. Loftus, Ridgewood, N. J., assignor to
 Radium Chemical Company Inc., New York,
 N. Y., a corporation of New York

Application January 13, 1950, Serial No. 138,360

1 Claim. (Cl. 128—1.2)

1

My invention pertains to radium nasopharyngeal applicators particularly designed for treatment of lymphoid tissue in the nasopharynx.

In applicators heretofore used for treating lymphoid tissue in the nasopharynx with radium, the radium bearing material has been enclosed in a separate tube which has been threadedly attached to a rod-like handle. The radium carrying tubes of such prior applicators have been of larger diameter than the rod-like handles to which the tubes were threadedly attached so that an enlargement or shoulder was present at the point of connection between these parts.

A primary object of my invention is to provide a new and improved construction for radium nasopharyngeal applicators which eliminates the need for a separate tube for the radium bearing material and a threaded connection between such tube and a rod-like handle.

Another object of my invention is to provide a new and improved radium nasopharyngeal applicator which encloses the radium bearing material in a rod-like part of uniform size and smooth exterior.

A further object of my invention is to provide a new and improved radium nasopharyngeal applicator which may be readily and inexpensively made of conventional materials by the utilization of existing manufacturing procedures.

Other objects and advantages will become apparent as the description proceeds.

In the drawings:

Fig. 1 is a side elevational view on an enlarged scale of a preferred embodiment of my invention;

Fig. 2 is a view similar to Fig. 1 but on a larger scale and with parts cut away to reveal details of internal construction;

Fig. 3 is an enlarged detail sectional view illustrating one way of sealing in the radium bearing material; and

Fig. 4 is a view similar to Fig. 3 but showing another method of sealing in the radium bearing material.

Referring particularly to Fig. 1 it will be seen that my novel applicator comprises an elongated rod 10 of uniform outside diameter and having a smooth external surface throughout its exposed length. The rod 10 may be formed of "Monel" metal or other suitable material and is threadedly attached at one end to a handle part 12 as indicated at 14 in Fig. 2. The handle part 12 may be formed of steel or any other suitable material and is preferably provided with a knurled external surface to facilitate nice manipulation of the applicator during a treatment.

The end of the rod 10 which is remote from the metal part 12 is drilled to provide a recess 16 for receiving the radium bearing material 18. The extreme free end of the rod 10 is preferably provided with an internal thread for receiving a

2

threaded plug such as the plug 20 of Fig. 3 or the plug 22 of Fig. 4.

In the form of construction shown in Fig. 3 the plug 20 may be part of a threaded rod 24 which is screwed into the free end of the rod 10 and then cut off even with the end of the rod 10. Solder 26 may then be applied to the end of the plug 20 and rod 10 to prevent removal of the plug. This solder is preferably formed to provide a rounded end which facilitates insertion of the applicator without injury to the patient's tissues.

In the alternative construction of Fig. 4 the plug 22 has a threaded end of reduced diameter which screws into the end of the rod 10 and an enlarged end of the same diameter as rod 10 which constitutes a continuation thereof. This enlarged end serves as a means for screwing the plug into the rod 10 and is preferably rounded as indicated at 28 to facilitate insertion of the applicator into the nasal passages. An annular recess 30 is preferably provided between the end of the rod 10 and the enlarged part of the plug 22. This recess is filled with solder to render the plug non-removable.

While I have illustrated and described in detail only two embodiments of my invention, it is to be understood that my invention is not limited to the particular details shown but includes all variations, modifications, and equivalents coming within the scope of the appended claim.

I claim:

A nasopharyngeal applicator for treating with radium comprising an elongated rod of one piece construction and of uniform external diameter, said rod having a handle part at one end and an elongated chamber drilled in the other end thereof, radium bearing material in said chamber, the chamber end of said rod terminating in an internally threaded part, and a non-removable closure for said chamber secured to said threaded part and sealing said chamber, said closure and rod being soldered to form a smooth joint and prevent separation of said closure and rod, said applicator having a smooth outer surface for insertion into a nasal passage and a rounded end surface merging into said first-named surface.

GEORGE H. LOFTUS.
